United States Patent

Des. 240,897
Patented Aug. 10, 1976

240,897

BOTTLE OR SIMILAR ARTICLE

John W. McDonald, Kansas City, Mo., assignor to Ethyl Development Corporation, Kansas City, Mo.

Filed Mar. 3, 1975, Ser. No. 554,602

Term of patent 14 years

Int. Cl. D9—01

U.S. Cl. D9—87

FIG. 1.

FIG. 2.

FIG. 3.

FIG. 4.

FIG. 1 is a front elevational view of a bottle or similar article embodying my new design;

FIG. 2 is a side elevational view thereof;

FIG. 3 is a bottom plan view thereof; and

FIG. 4 is a top plan view thereof.

I claim:

The ornamental design for a bottle, or similar article, substantially as shown.
